A. BLOOD.

Steam Heater.

No. 17,483.

Patented June 9, 1857.

UNITED STATES PATENT OFFICE.

ASA BLOOD, SR., OF NORFOLK, VIRGINIA.

IMPROVED STEAM-HEATING STOVE.

Specification forming part of Letters Patent No. 17,483, dated June 9, 1857.

To all whom it may concern:

Be it known that I, ASA BLOOD, of Norfolk, in the county of Norfolk and State of Virginia, have invented a new and Improved Parlor-Stove, to be known and used as the "American Star Stove;" and I do hereby declare that the following is a full and exact description thereof, reference being had to the accompanying drawings, and to the letters of reference marked thereon.

In the drawings, Figure 1 is an isometrical view of the stove with one of the sliding doors and screens removed. Fig. 2 is a plan view, with a part of the stove through the line x x removed. Fig. 3 is an isometrical view of a wood-burning grate. Fig. 4 is an end view of Fig. 3, showing the grate-bars and shaker. Fig. 5 is a view of the coal or ash box and sifter. Fig. 6 is a plan view of a coal-burning grate. Fig. 7 is a plan view of a grate with hollow cylinder-bars. Fig. 8 is an end view of the same. Fig. 9 is a view of a toothed shaker. Fig. 10 is a view of a toothed shaker somewhat different from the one shown in Fig. 9.

The nature of my invention consists in making a stove greatly improved for the purpose of burning wood or coal and heating by the aid of hot air and steam.

To enable others skilled in the art to make and use my invention, I will proceed to describe its construction and operation.

In the construction of my stove, in Fig. 1, A are the legs; B, the lower chamber for ashes and cinders; C, the ash-pan; D, the ash-sifter; E, the steam and hot-air chamber; F, the handle to operate the ash pan and sifter; G, crank for operating the grate; H, H', and H², the hollow steam-chambers, two of them, H' and H², being divided by a partition through the center, thus forming two passages in each pillar; I, screen-doors; J, grate with hollow bars; K, angular hollow columns through which pass the holes b for the passage of the products of combustion into chamber L'; L, the slide-doors operating in grooves attached to hollow pillars H and H'; L', the top chamber for containing steam and the products of combustion; outside of the dotted lines in Fig. 1 is the steam-chamber; inside of the same is for containing the products of combustion; M, the pillars for the passage of the effects of combustion, conveying it into cham-

ber O; M', passage for steam; N, the water-chamber; O, the upper chamber for the products of combustion to enter and pass through; P, the cap to the stove; Q, the pipe or exit-passage for the products of combustion and the steam; R, escape-cocks for letting off the steam; S, funnel-shaped pipe for feeding water to the chamber N; R', the tube for carrying off the steam into the room or for purposes of cooking, if desired.

In Fig. 2, E is the lower steam-chamber; II, pillar for the passage of steam, H' and H² being divided, each having two passages through it; or instead of two chambers in one pillar I may find it more convenient to use two pillars; K, angular hollow columns for the effects of combustion to pass up into the chamber L'; N, the water-chamber; a, tubes passing through the water-chamber and open at both ends to allow the products of combustion also to pass through, thus aiding in the generating of steam.

In Fig. 3, 1 are the vertical bars; 2, the bottom bars; 3, the shaker-bars; 4, the shaker-shafts.

In Fig. 4, c are the vertical bars; d, the shaker; d', bottom bars shown in dotted lines; d², the shaft.

In Fig. 5, e is the ash-pan; f, the coal-sifter; f', the sifter-handle.

In Fig. 6, g is the bottom plate; h, the bar, forming the bottom of the grate; i, the shaker; i', the shaft.

In Fig. 7, j are the bottom plates; k, tubular bars; l, the shaker; l', the shaft.

In Fig. 8, m are hollow bars of grate; n, the shaker; o, the end of rock-shaft, on which the shaker operates.

In Fig. 9 is a side view of the shaker.

In Fig. 10, p is the toothed shaker; q, the eccentric crank to operate the grate.

In the operation of my invention the water to be converted into steam is conveyed into the water-chamber N through the receiving-tube S, which tube passes down nearly to the bottom of the chamber, thus conveying the cold water directly to the bottom of the chamber, and also to prevent the escape of steam through the tube. The steam in water-chamber N enters through a tube shown in dotted lines into pillar M', then through tube seen in red lines into pillar H', following the direction of the arrows passing into

chamber E, filling said chamber as far as the dotted line in said chamber, then up pillar H into chamber L', filling said chamber as far as the partition seen in dotted lines above pillar H', then down one side of said pillar into chamber L, filling said chamber as far as the partition 2 in dotted lines, then up the other side of said pillar into chamber L' and down pillar I I again into chamber E and up pillar H', through the tube in dotted lines into pillar M', and the tube in dotted lines in chamber O and pipe R, when it is let off by the stop-cocks into pipe Q, or it may be carried off into the room for other purposes. The tube R' has an orifice in it seen in dotted lines. A tube is seen at a', Fig. 1, extending from the grate into chamber E for conveying the steam or what parts of it may become condensed into the hollow grate; then passing through it, it passes out of the tube R' in the orifice in the said tube into pillar H', and is carried off, as described. The steam taken from the stove either at R' or R can be used for cooking purposes or for bathing by attaching a conducting-tube to either of them. The products of combustion pass up the angular flanges K, through holes b and tubes a, into the inner portion of the chamber L', then through pillars M into chamber O and thence through the pipe Q and is carried off.

In the operation of my grate I can easily displace one and insert another when I wish to burn wood or coal in the same stove. The shaft o in Fig. 8 has a slot, into which the tenon on the end of the shaft to which the crank q in Fig. 10 is attached slips into the slot, and thus forms a permanent attachment. To make this connection, it is only necessary to bring the crank and the shaker in a vertical position, and then the grate can be lifted out and another set in. By means of the shaker-bars in Fig. 10, operating on an eccentric, they have an uplifting movement, passing easily up into the coal and lifting it up, causing the ashes to fall into the sifter.

By means of the sifter in the ash-pan I am enabled to sift the ashes from the coal and preserve the coal and cinders, this being done inside of the ash-chamber, which fits tightly and does not allow any of the dust to enter the room.

In the operation of my slide-doors when I first make the fire, all of them may be slid down, rendering the stove air-tight. To create a draft it will only be necessary to draw out the ash-pan, so that the draft can pass through it, through the grate or fire, and through the tubes a and holes b, as before described. After the fire has commenced to burn, I can move up all the outside slides or doors, leaving the perforated doors standing, so that the fire will shine through them; or all can be raised, leaving the fire exposed on all sides, and as high as may be desired to decrease the draft and expose the fire; or only one or more of the sides of the burning grate may be exposed, leaving the other sides down.

This stove has then all the comfortable appearance of a grate-fire, with much more heat. If all the doors are lifted a few inches, the stove will present a lively and cheerful appearance fully equal to a wood-fire.

It will be seen Fig. 8 represents a hollow grate; and I intend to make all my grates thus, because of their convenience and durability, and for using the steam for heating purposes, and for preserving a healthy state of atmosphere in the room.

Having thus described the construction and operation of my invention, what I claim as new, and desire to secure by Letters Patent, is—

The arrangement of the water-chamber N, chambers E and L' and O, pillars H, H', and H'', hollow grate, and tubes R and R', as set forth.

ASA BLOOD, SENR.
